UNITED STATES PATENT OFFICE.

WILLIAM HENRY STIEGELMAIER, OF GENEVA, NEW YORK.

ELECTRIC TEMPERATURE-ALARM AND THERMOSTAT.

SPECIFICATION forming part of Letters Patent No. 351,134, dated October 19, 1886.

Application filed February 2, 1886. Serial No. 190,621. (No model.)

To all whom it may concern:

Be it known that I, WILLIAM HENRY STIEGELMAIER, of Geneva, in the county of Ontario and State of New York, have invented a new and useful Improvement in Electric Temperature-Alarms and Thermostats, of which the following is a specification, reference being had to the annexed drawings, forming a part thereof, in which—

10 Figure 1 is a front elevation. Fig. 2 is a vertical transverse section taken on line *x x* in Fig. 1. Fig. 3 is a detail view of a modified form of electrical contact.

Similar letters of reference indicate corresponding parts in the different figures of the drawings.

15 The object of my invention is to provide an accurate and efficient device for making and breaking an electric circuit by the rise and fall of temperature.

20 My invention consists in the combination, with the mercury tube and case of a balance-thermometer, of an electric contact carried by the tube and adjustable contact-points arranged in the back of the thermometer-case in position to be touched by the contact carried by the tube, as hereinafter more fully described.

25 The case A and balanced mercury-tube B of the balance-thermometer are of the usual well-known description, the case A being of sectoral form, having the curved scale C in the wider end. To the non-conducting back of the casting, concentric with the scale C, is placed a 30 U-shaped support, D, having in the upper ends of its arms cups for receiving the points *a*, forming the pivots of the thermometer-tube. The points *a* are formed integrally with the strip *b*, which is returned upon itself, the two 35 arms of the strip being connected by an adjusting-screw, *a'*. The strip *b* is secured adjustably to the tube of the thermometer by a winding, *d*, of wire. To the strip *b* is secured a copper strip, *e*, which extends along the upper surface of the tube of the thermometer, 40 parallel with it, then around the bulb of the thermometer, and under the thermometer-tube, the remaining extremity being received under the wire winding *d*. The U-shaped support 45 D and the strip *b* are in electrical connection

with each other and with the wire conductor *f*, which leads to the battery E.

50 In the back of the thermometer-case is formed a curved slot for receiving the two curved slides *g g'*, inserted from opposite sides of the 55 casing. The slides *g g'* are retained in place in the groove in the thermometer-case by a slotted curved plate, *h*, which covers the edges of the slides. Each slide *g g'* is provided with an electrical contact-pin, *j*, which projects outward into the case of the thermometer through the slot of the plate *h* into the path of the thermometer-tube, so that as the thermometer-tube rises or falls the strip *e* may strike one or the other of the contact-pins *j*. 65

60 For convenience in adjusting the contact-pins *j*, the edge of the plate nearest the pivot of the thermometer-tube is provided with a scale, *i*, corresponding with the scale C, but necessarily placed in an inverted position, on 70 account of being on the opposite side of the pivot of the thermometer-tube. 75

65 To insure a good electrical contact with the slides *g g'*, the bottom of the groove in which these slides are placed is provided with a metallic plate, *k*. The metallic plate *k* is connected by a wire, *l*, with one binding-post of an electrical bell, *F*, which may be of any ordinary well-known construction, the other binding-post of the bell being connected by the 80 wire *m* with the remaining pole of the battery E.

75 Instead of taking the current through the support and pivots of the thermometer-tube, as already described, I may, as in Fig. 3, attach to the tube an arm, *e'*, arranged to touch 85 the pins *j*, and I may connect the arm *e'* directly with the battery by means of the wire *f*.

80 The slides *g* are adjusted according to the marks on the scale *i*, so that the strip *e*, carried by the thermometer-tube, will touch them 90 when the maximum and minimum of temperature is reached. When the mercury falls in the tube, the weight of the bulb of the tube being increased, that end of the tube preponderates and brings the strip *e* into contact with 95 the pin *j* of the lower slide, *g'*, and when the mercury in the tube expands the bulb becoming lighter, the opposite end preponderates and brings the strip *e* into contact with the contact-pin *j* of the upper slide, *g*. By 100

means of this arrangement the electric circuit is completed and an alarm is given whenever the strip *e* strikes either of the pins *j*.

It will be observed that the slides *g g'* may

5 be adjusted so as to cause an alarm at any point, and the contact-pins *j* may be placed so near the strip *e* as to cause an alarm to be given by the variation of a fraction of a degree.

10 My improved alarm and thermostat may be connected with an electro-magnetic damper-regulator for furnaces or with the regulators of incubators. It may also be employed to great advantage in greenhouses, and in other

15 places where a constant temperature is desired. It may be used as a thermostat for giving automatic fire-alarms, and in other places where only the maximum or minimum of temperature is to be indicated. In the case of a maximum temperature the upper contact-pin *j* only need be used, and where an alarm is desired for a minimum temperature only the lower contact-pin *j* may be used.

Having thus described my invention, what I 25 claim as new, and desire to secure by Letters Patent, is—

1. The combination, with a balance-thermometer tube and its conductive fulcrum, of a sustaining case or frame supporting said fulcrum and having two sets of graduations, one upon each side of the fulcrum, and reading or 30 progressing in opposite directions, a conducting-strip carried by the thermometer-tube and electrically connected to the fulcrum, and one 35 or more adjustable contact-points supported

by the frame or case and disposed in range of engagement with the electrical connection of the fulcrum, substantially as and for the purpose described.

2. The combination, with the casing A and balanced thermometer-tube B, of the metallic support D, fixed to the non-conducting back of the casing, the pivotal points *a*, attached to the thermometer-tube, the contact-strip *e* in electrical contact with the points *a* and support D, and one or more adjustable contact-pins *j*, supported by the back of the thermometer-case, substantially as herein shown and described.

3. The combination, with the casing A and balanced mercury-tube B, of the metallic support D, the points *a*, the metallic strip *e*, in electrical communication with the points *a* and support D, the slides *g g'*, received in a groove in the back of the thermometer-case, and carrying contact-pins *j* on opposite sides of the thermometer-tube, substantially as herein shown and described.

4. The combination, with the balanced mercury-tube B, metallic strip *e*, and electrical conductors connected therewith, of the adjustable slides *g g'*, carrying the contact pins *j*, and the auxiliary scale *i*, substantially as herein shown and described.

WILLIAM HENRY STIEGELMAIER.
